US0D1096101S

(12) **United States Design Patent** (10) **Patent No.:** **US D1,096,101 S**
(45) **Date of Patent:** **** Oct. 7, 2025**

(54) **SHOE SOLE**

(71) Applicant: **Quanzhou Yudong E-commerce Co., Ltd.**, Quanzhou (CN)

(72) Inventor: **Xing Zhang**, Guixi (CN)

(73) Assignee: **Quanzhou Yudong E-commerce Co., Ltd.**, Jiangxi (CN)

(**) Term: **15 Years**

(21) Appl. No.: **29/984,309**

(22) Filed: **Jan. 14, 2025**

(51) LOC (15) Cl. **02-04**

(52) U.S. Cl.

Primary Examiner — Jonathan J Han

(57) **CLAIM**

The ornamental design for a shoe sole as shown and described.

DESCRIPTION

FIG. 1 is a top perspective view of a shoe sole showing my new design;

FIG. 2 is a bottom perspective view thereof;

FIG. 3 is a left side elevational view thereof;

FIG. 4 is a right side elevational view thereof;

FIG. 5 is a rear elevational view thereof;

FIG. 6 is a front elevational view thereof;

FIG. 7 is a top plan view thereof;

FIG. 8 is a bottom plan view thereof; and,

FIG. 9 is an enlarged view of the area identified as "9" in FIG. 2.

The dot-dash broken lines in FIGS. 2 & 9 are used to identify an area of enlargement, with the dot-dash broken lines forming no part of the claimed design.

1 Claim, 9 Drawing Sheets
